UNITED STATES PATENT OFFICE

JAMES S. THOMPSON, OF NEW YORK, N. Y., ASSIGNOR TO FIREBAR CORPORATION, OF CLEVELAND, OHIO, A CORPORATION OF DELAWARE

GRATE

Application filed November 12, 1929. Serial No. 406,558.

This invention relates to fuel grates and is concerned more particularly with a grate bar of novel construction especially adapted for use in boiler furnaces, locomotive fire boxes 3 and like structures.

The grate bar of the invention is constructed to provide a wide distribution of the air used for combustion to all parts of the fuel bed supported on the bar. To this end, 10 the bar is provided with a multiplicity of separated fuel-supporting areas of small dimensions so that only a small proportion of the bottom surface of the layer of fuel is in actual contact with a solid surface of the bar. 15 and the "dead spaces" in the bottom of the fuel bed are thus reduced to a minimum consistent with proper support. In order to insure that the air flowing through the bar from the ash pit to the fuel will not be concentrated and delivered to certain localized areas, as is the case with present bars, the new bar is provided with air passages through it of constantly decreasing cross-sectional area from bottom to top of the bar. 20 The upper ends of these passages where the constriction is greatest are in effect orifices through which the air flows to the fuel, and at these orifices there is a substantial pressure drop which is utilized to accomplish horizontal 25 distribution of the air.

The fuel-supporting surface of the bar is subdivided by air channels which extend substantially horizontally and these channels communicate with the air passages below the 30 point of maximum constriction thereof, so that as the air flows up through the bar, it reaches the ends of the channels just before it reaches the main orifices, and there is an effective pressure drop in the channels which 35 results in the air flowing along the channels and laterally across the upper surface of the bar. The constriction of the passages above the bottom of the channels further promotes 40 the lateral flow, since it offers resistance to the direct upward flow of air through the passages beyond the ends of the channels. In the improved construction, therefore, wide 45 horizontal flow and distribution of the air to all parts of the under surface of the fuel

bed are obtained with improved combustion efficiency.

Due to the fact that the bottoms of the channels are formed with a slight upward inclination away from the air passages, ashes 55 which collect in the channels tend to slide down the channels to the passages and fall through the latter to the ash pit. Also, since each fuel-supporting area on the grate is relatively small and air flows around it on all 60 sides, the grate is protected against burning out and has a much longer life than former grate bars in which the dead spaces form a substantial part of the total area of the bars. 65

For a better understanding of the invention, reference may be had to the accompanying drawings, in which

Fig. 1 is a transverse section through one of the grate bars of this invention showing a fuel-supporting unit in side elevation;

Fig. 2 is a fragmentary plan view thereof;

Figs. 3, 4, 5, and 6 are sectional views on the lines 3—3, 4—4, 5—5, and 6—6, respectively, of Fig. 2; and

Fig. 7 is a sectional view on the line 7—7 of Fig. 1.

Referring now to the drawings, the bar is illustrated as consisting of a longitudinal supporting member 10 having an upwardly extending flange 11, a plurality of cross-bars 12 being supported loosely on member 10. The supporting member is provided at each end with a trunnion 13 and has a downwardly extending shaker arm 14 by which it can be connected to a shaker rod in the usual manner. Each supporting member carries a plurality of the cross-bars loosely mounted thereon and readily removable from the supporting member in an upward direction. The provision of cross-bars loosely mounted on a supporting member forms no part of my invention, but is set forth and described in a co-pending application of Buckley, Serial No. 338,352, filed February 8, 1929. The features of grate bar construction which constitute my invention may be incorporated in a bar of the Buckley type in which the cross-bars are removable from the supporting member or may be employed in a grate

bar in which the cross-bars and supporting member are formed as an integral unit.

- Each cross-bar extends laterally with respect to the supporting member for a substantial distance and the cross-bar includes a plate-like body 15, which is of gradually increasing thickness from the lower edge 16 to the top 17. On each face of the cross-bar is a series of lugs 18 extending downwardly a substantial distance from the top thereof. These lugs increase in width from their lower end 19 to the top 20 and also increase in thickness, as illustrated more clearly in Fig. 4. The distance between the opposed sides of adjacent lugs at their lower ends is thus substantially greater than the distance between these sides at the upper ends of the lugs. The cross-bars lie side by side on the supporting member and are kept in the desired spaced relation by spacing projections 21 formed as a part of the lugs 18. There is a pair of projections on each side of the cross-bar and the projections on adjacent cross-bars contact, as illustrated in Fig. 7, as to provide the proper spacing between the cross-bars on the supporting member. When the cross-bars and supporting member are formed integrally, the spacing projections are omitted.
- Formed in the upper surface of the plate-like body of the cross-bar is a longitudinal channel 22 and there are also other channels 23 and 24 in the top of the cross-bar extending transversely thereof. Each transverse channel 23 communicates at its ends with a space between a pair of adjacent lugs, while each transverse channel 24 extends directly across the cross-bar and across the tops of a pair of lugs 18 in registry on opposite sides of the cross-bar body. Each lug is also provided with an air channel 25 which extends across the lug from one side to the other. The bottoms of the various air channels have an inclination as follows:
- There is a high point 26 in the longitudinal channel 22 at each intersection of the channel 22 with a transverse channel 24, and the channel 24 slopes downwardly from the point 26 in each direction toward the outer ends 27 of lugs 18. The channel 25, intersecting channel 24 and lying in the top of one lug, slopes downwardly in each direction from the point of intersection designated 27. The channel 23 slopes downwardly in each direction from its point of intersection 28 with the channel 22. With this arrangement, it will be observed that there is a high point in the channel 22 on the median line of each pair of lugs and low points in channel 22 where the channels 22 and 23 intersect. Each channel 23 leads downwardly from each of the points 28 and the bottom of channel 23 at its outer end lies in substantially the same plane as the bottom of the channel 24 at each end of the latter.

Between adjacent cross-bars there is an air passage 29 for the upward flow of air from the ash pit to the fuel supported on top of the cross-bars. Since each cross-bar is of increasing thickness from bottom to top and each lug 18 is also of increasing cross-sectional area from bottom to top, it will be apparent that the air passages are gradually restricted in an upward direction. Since there is atmospheric pressure in the ash-pan below the grate and a partial vacuum in the fire-box above the grate due to the draft, the upper end of each passage constitutes an orifice at which a drop in pressure occurs. The point of maximum constriction of the passage is at the top of the cross-bar and the several channels 23, 24, and 25 communicate with the air passage below this point. Consequently each of these channels may be considered to constitute a minor orifice at which a pressure drop occurs. As a result, when the air drawn upward through the grate reaches the ends of the channels, it flows along the channels in a generally horizontal direction and thus is distributed to all parts of the under surface of the bed of fuel. Since the channels open into the passages below the point of maximum constriction thereof, the further constriction of the passages above the channels offers resistance to the direct upward flow of the air which assists in changing its direction and causing its distribution in the manner described.

The channels lying in the fuel-supporting surface of the cross-bar and lugs sub-divide this surface into a plurality of small fuel-supporting areas and air flows in contact with the metal on all sides of each area. The cooling effect of the air reduces the temperature of the metal and consequently prevents burning out of the fuel-supporting parts of the bar, and thus increases the life of the bar.

The entire bed of fuel is supported on small separated surfaces, which together represent only a small fraction of the total area of the bar. Each fuel-supporting surface represents dead space and air cannot reach the fuel above such a dead space. However, since the dead spaces in the new bar are so small and air is delivered to the fuel on all sides of each dead space, the necessary support is given to the fuel without interfering to any substantial extent with the delivery of air to all parts of the fuel bed. In actual practice, it has been found possible in a bar of the present construction to support the fuel properly on a multiplicity of these supporting surfaces which have an aggregate area amounting to approximately 12½ per cent. of the total area of the grate bar. Consequently in this bar, the dead space is reduced far beyond that which occurs in grate bars of the construction heretofore employed, and the reduction of dead space is accomplished not only with the provision of proper

support but in such a way as to provide a better air distribution.

Each of the air channels in the top of the cross-bar and of the lugs has an upward inclination away from the air passage of adjacent cross-bars and this serves the useful purpose of assisting in the removal of the ash. Because of the excellent air distribution, fuel burned on a grate bar of the present construction is consumed to a fine ash which drops into the several air channels.

The bottoms of these channels incline downwardly toward the air passages, and the ash slides down through the channels to the passages and thence falls into the ash pan. This self-cleaning action is greatly facilitated when the cross-bar is mounted loosely on the supporting member in accordance with the Buckley invention, but also occurs in the case of a solid bar and particularly, when the latter is mounted in a frame structure subjected to frequent jarring, as, for instance, in locomotives. The slight upward inclination of the air channels away from the air passages does not interfere with the proper lateral flow of the air, since the tendency of the air is to flow in a general upward direction from each of the channels to the fuel bed.

It will be observed that in a grate made up of the new bars, air can flow through each bar between adjacent cross-bars and air can also flow between the opposed ends of a pair of cross-bars on adjacent supporting members. Each cross-bar is generally of half-moon shape, as shown more clearly in Fig. 1, so that the passage between the ends of adjacent cross-bars on different supporting members is also gradually constricted in a direction toward the fuel bed. Accordingly, throughout the grate made up of these new grate bars, air drawn up through the grate by the draft passes through orifices before it reaches the fuel and the pressure drop results in the desired horizontal flow of the air which insures wide distribution thereof to all parts of the fuel bed. With grate bars as heretofore constructed, the air flows directly up through air passages in the bars to the fuel bed and little or no lateral flow in contact with the bottom of the fuel bed occurs. The air is accordingly delivered to the fuel in localized areas and there are many dead spaces in the fuel bed where the combustion of fuel takes place in a sluggish manner. In the present grate bar, the dead spaces have been reduced to a minimum consistent with the proper support of the fuel, and in addition the distribution of the air occurs in such a way as to cool the parts of the bar which actually support the fuel. Much better combustion is thus obtained and the grate bar has a prolonged life.

What I claim:

1. A grate bar comprising fuel supporting

means and provided with passages for air to the fuel supported by said means, said passages being of decreasing size from bottom to top thereof and terminating in orifices at their upper ends, said fuel supporting means being further provided with open top channels to sub-divide its upper portions into a multiplicity of small fuel-supporting surfaces, said channels communicating with said passages below the point of maximum constriction thereof. 75

2. A grate bar comprising spaced fuel-supporting members defining passages for air from the under side of the bar to the fuel supported thereon, said passages being of increasing constriction from bottom to top of said members and terminating in orifices at their upper ends, and said members being provided with channels extending generally horizontally and sub-dividing said members into a plurality of small separated fuel-supporting areas, said channels communicating with said passages below the point of maximum constriction thereof and constituting minor orifices at which occurs a pressure drop effective to promote horizontal flow of the air beneath the fuel bed. 80

3. A grate bar which includes a plurality of cross-bars disposed side by side in a row and spaced to provide passages for the upward flow of air between them, said cross-bars being formed to effect constriction of said passages, and a plurality of substantially horizontal air channels in the tops of said cross-bars, said channels communicating with said passages below the point of maximum constriction of the passages. 95

4. A grate bar which includes a plurality of cross-bars, the upper surfaces of which constitute a fuel support, said cross-bars being spaced to provide passages for the upward flow of air between them to the fuel supported by the bars, said passages being gradually constricted from the bottom toward the top, and air channels sub-dividing the fuel-supporting surface of each cross-bar and communicating with said air passages at a point below the maximum constriction thereof. 105

5. A grate bar which includes a plurality of cross-bars placed side by side, the top of each cross-bar providing a fuel-supporting surface, said cross-bars being spaced to provide passages for the upward flow of air between them, said passages being increasingly constricted from bottom to top thereof, and intersecting air channels in the top of each cross-bar sub-dividing the fuel supporting surface thereon, said air channels communicating with the air passages below the point of maximum constriction thereof and extending substantially horizontal with a slight upward inclination away from said passages. 110

6. A grate bar which includes a plurality 120

of cross-bars disposed side by side, each cross-bar having a series of spaced lugs on each side thereof, opposed sides of adjacent cross-bars with their lugs defining air passages for the upward flow of air between them, said cross-bars and lugs being formed to effect gradual constriction of each passage from the lower intake end to the upper discharge end thereof, the upper surfaces of each cross-bar with its lugs serving to support the fuel, and air channels subdividing said surfaces and communicating with said passages below the point of maximum constriction thereof, each cross-bar having a longitudinal channel and spaced transverse channels communicating therewith.

7. A grate bar which includes a plurality of plate-like members disposed side by side in spaced relation, each member having a series of spaced lugs on each side thereof, the lugs of the two series being oppositely disposed, said members being spaced to provide passages for the upward flow of air between them, each passage being of decreasing cross-sectional area from the lower intake end thereof to the upper outlet end, the top of each member with its lugs providing a fuel-supporting surface, and open-top air channels sub-dividing said surface and communicating with said air passages below the outlet ends thereof, said members having a central longitudinal channel and spaced transverse channels, certain of the latter channels extending over the tops of opposite lugs.

8. A grate bar comprising a longitudinal member and a plurality of cross-bars extending beyond said member laterally thereof, each cross-bar having a plurality of lugs on each side face thereof and connecting air channels in the upper faces of the cross-bar and lugs, said cross-bars being of increasing thickness from bottom to top and being spaced to provide air passages of decreasing cross-section from bottom to top of the cross-bars, the channels communicating with the passages below the point of maximum constriction of said passages.

9. A grate bar comprising a longitudinal member and a plurality of cross-bars extending beyond said member laterally thereof, each cross-bar being provided on each side face with a series of tapering lugs extending down from the top surface of the cross-bar and of increasing cross-section from bottom to top, adjacent lugs in part defining an air passage of decreasing cross-sectional area from bottom to top of said lugs, and air channels in the top of the cross-bar and said lugs, said channels communicating with said passages below the point of maximum constriction thereof.

10. In a grate bar, a fuel-supporting member having a plurality of lugs on each side face thereof and connecting air channels in

the tops of the member and lugs, said lugs being of increasing size in an upward direction and partly defining air passages of decreasing size, said air channels communicating with said passages below the point of maximum constriction thereof.

11. In a grate bar, a fuel-supporting member having a series of spaced lugs on at least one side thereof, said lugs extending downwardly from the top of the member and decreasing in size from their tops to their lower ends, adjacent lugs in part defining vertical air passages of increasing constriction upwardly, and open top air channels in the upper faces of the lugs and member, said channels communicating with the passages below the point of maximum constriction of said passages.

In testimony whereof I affix my signature.
JAMES S. THOMPSON.
